[57] CLAIM

The ornamental design for an electric massager, as shown and described.

DESCRIPTION

FIG. 1 is a front elevational view of an electric massager showing our design;

FIG. 2 is a rear elevational view thereof;

FIG. 3 is a top plan view thereof;

FIG. 4 is a bottom plan view thereof;

FIG. 5 is a right side elevational view thereof, the left side elevational view being identical; and,

FIG. 6 is a right side elevational view thereof in extended condition.

*Fig. 1**Fig. 2**Fig. 3**Fig. 4**Fig. 6*
